FIRE WALL AND TANK INSTALLATION

Gerald L. Brennan, Tulsa, Okla., assignor to Warren Petroleum Corporation, Tulsa, Okla., a corporation of Delaware

Application February 18, 1952, Serial No. 272,040

8 Claims. (Cl. 220—88)

1

This invention consists in new and useful improvements in a fire wall and tank installation for the storage of inflammable fluids and has for its object to provide a structure which will minimize the fire hazards presently existing in and around such facilities.

In installations such as shipping terminals and storage depots for liquefied petroleum gas and the like, it is customary to employ batteries of large, horizontally disposed storage tanks, arranged in relatively close proximity and provided with the necessary piping connections for charging and discharging the fluid to be stored. In a number of instances very serious fires have occurred because of the failure of a joint or a section of pipe near a joint beneath one of the tanks in a battery, with the resulting escape of large volumes of inflammable fluid which, upon ignition, have rapidly enveloped the nearby tanks in flame. These tanks are often of an individual capacity of 30,000 gallons and when one or more batteries of such tanks are involved, it will readily be seen that fire hazards can present a serious problem.

The effect of this heat has naturally been to increase the pressure of the fluid in the tanks to a point where the metal and seams of the tanks were forced to yield, with the resultant opening up of seams or bursting of tanks. Thus, the escape of more inflammable fluid has added fuel to the fire to such an extent that in most instances the entire installation has rapidly suffered serious damage.

It is, therefore, the primary object of the present invention to increase the safety of such installations and to provide adequate fire protection to the metal of the tanks and to this end I have provided a fire wall which is arranged transversely, across the end of a battery of tanks and through which the tank heads protrude. All of the inlet and outlet openings and their associated pipings are connected into these heads and are thus separated from the main bodies of the tanks, whereby any ignition of escaping fluid in and around the piping system is at least temporarily confined to an area which is completely segregated from the tanks themselves.

Another object of the invention is to provide a fire wall preferably provided with angularly disposed wings at its opposite extremities to form a three-sided enclosure or fire shield for the head ends of a battery of tanks, the bounding edges of the shield being provided with a continuous, forwardly-directed flame-diverting lip which tends to localize the flames and adds further protection against their spreading to the tanks proper, or to other batteries of tanks.

2

A further object of the invention is to provide a fire wall of the type referred to, wherein the protruding heads of the battery of tanks are each covered with a fire proof insulation which further reduces the sudden overheating of the tanks in the area where ignition of escaping fluid is most likely to occur.

With the above and other objects in view which will appear as the description proceeds, my invention consists in the novel features herein set forth, illustrated in the accompanying drawings, and more particularly pointed out in the appended claims.

Referring to the drawings in which numerals of like character designate similar parts throughout the several views,

Figure 1 is a perspective view of a portion of the fire wall, partly in section, and showing the heads of two tanks protruding therethrough.

Figure 2 is a top plan view showing an entire installation on a smaller scale.

Figure 3 is a view in side elevation, partly in section.

Figure 4 is a sectional view taken on line 4—4 of Figure 3.

Figure 5 is a fragmentary view showing a portion of the main fire wall or shield, with a tank-receiving opening, and

Figure 6 is a fragmentary view showing a portion of the rear tank support with its tank-receiving recesses.

The drawings represent a typical tank installation embodying the improved fire wall and consisting of a battery of horizontally-disposed tanks 7, supported in laterally spaced relation by upright fore and aft foundations. The rear foundation 8 is formed of poured reinforced concrete, preferably having an enlarged footing 9 beneath the surface of the ground, said foundation extending transversely across the entire battery of tanks. The upper edge of foundation 8 is provided with a series of arcuate recesses 10, spaced at suitable intervals to coincide with the desired spacing of the tanks which are to be cradled in the recesses 10, the height of the foundation being such as to maintain the tanks at the desired elevation above the surface of the ground.

The forward foundation 11 is essentially of the same structure as the rear foundation and has an underground footing 12. However, the upper end of foundation 11 is extended vertically to form the main shield 13 of the fire wall which, as will be seen from the drawings, may be of slightly reduced thickness above the supporting foundation 11. The shield 13 is provided with a series of circular openings 14, transversely spaced

to coincide with the spacing of the recesses 10 in the rear foundation 8 and having radial dimensions to accommodate the forward ends or heads of respective tanks 7. Preferably, the upper horizontal edge of the shield 13 is thickened and extended forwardly at substantially 45°, to form an outwardly-directed flame-diverting lip or flange 15 for purposes hereinafter described.

The opposite longitudinal extremities of the shield 13 terminate in forwardly-extending end wings 16, preferably arranged at right angles with respect to the shield 13 and the top and free vertical edges of these wings are provided with continuations of the angular flame-diverting lip, indicated at 17 and 18 respectively. Thus, the shield 13 and end wings 16, together, form a three-sided enclosure for the head ends of the battery of tanks, with a continuous fire-diverting lip extended entirely around the free edges or boundaries of the fire wall.

As before stated, the foundations 8 and 11 are preferably formed of reinforced concrete and the fire wall, including the main shield portion 13 and the end wings 16, are formed of similar material. Because the fireproof or refractory characteristics of the fire wall are essential to the successful functioning of the present invention, the cross-hatching on the drawings indicates a refractory material and in this connection it may be stated that instead of being formed completely of reinforced concrete, the fire wall may be composed of any suitable refractory material. Furthermore, the foundation 11 per se, may be formed of reinforced concrete and the fire wall, including the main shield 13 and end wings 16, may be composed of suitable refractory bricks or the like.

As will be seen from Figures 3 and 4 of the drawings, the head ends of the tanks 7 which protrude through the openings 14 in the shield 13, are covered with a suitable fireproof insulation or coating 19 and with the exception of tank relief valves 20, all connections to the tanks are preferably made through these insulated heads. In the form of the invention illustrated, valved inlets and outlets 21 and 22 are respectively connected by pipes 23 and 24, to supply and discharge headers 25 and 26. These headers extend transversely beneath the forward ends of the tanks 7 and are preferably supported in slightly elevated position by piping supports 27 which are formed integrally with the forward foundation 11 and its footing 12. These piping supports 27 are spaced so as to directly support the piping beneath each of the tanks of the battery.

With this arrangement it will be noted that not only are the heads of the tanks and their inlet and outlet openings confined within the boundaries of a three-sided fire wall, but all piping connections and headers in the immediate vicinity of the tanks are thus confined. The main shield portion 13 of the fire wall completely segregates all connections and piping from the main bodies of the tanks 7 and as these areas are the ones most likely to develop leaks, any fire resulting from such leaks will be prevented from contact with the tanks proper, at least for a sufficient period of time to permit adequate fire fighting equipment to be brought into play.

In the event of the ignition of any escaping fluid in the danger zone surrounding the piping and connections, the flame-diverting lips 15, 17, and 18, will tend to direct the flames away from the battery of tanks so as to concentrate the same within the confined area bounded by the

shield 13 and end wings 16. Thus, the extreme heat generated by such a fire will be prevented from contacting the tanks and effecting a dangerous increase in the pressure of the fluid stored therein.

From the foregoing it is believed that my invention may be readily understood by those skilled in the art without further description, it being borne in mind that numerous changes 10 may be made in the details disclosed, without departing from the spirit of the invention as set forth in the following claims.

I claim:

1. A fire wall and tank installation for above ground storage of inflammable fluids, comprising at least one horizontally disposed tank, located above the ground level, fore and aft foundations for supporting opposite ends of said tank, the forward foundation being formed of fire 15 resistant material and extending vertically to form the main shield of a transverse fire wall, an opening in said shield embracing the forward end of said tank and through which the head of the latter protrudes, said shield extending radially 20 in all directions, beyond the walls of said tank, the lateral extremities of said shield terminating in forwardly-directed wings of fire resistant material which, together with the main shield, form a three-sided fire wall, the upper edges of said 25 main shield and wings being provided with a continuous forwardly-directed horizontal flame-diverting lip having a free outer edge which overlies the area immediately adjacent the inner boundaries of the fire wall, all of the inlet and 30 outlet openings for said tank and their associated piping, being connected through the tank head and separated from the body of the tank by said main shield, and a coating of fireproof insulation 35 covering said protruding head.

2. A fire wall and tank installation as claimed in claim 1, including charging and discharging headers to which said inlet and outlet openings and their associated piping are respectively connected, said inlet and outlet openings, their associated piping, and the adjacent portions of said 40 headers being located within the confines of said 45 three-sided fire wall.

3. A combination above ground tank support and fire wall, comprising a solid foundation member, the top of which is recessed to provide a transverse cradle for the head end of a horizontal tank, said foundation being extended vertically to form a continuous fire wall of fire 50 resistant material, an opening in said fire wall adapted to embrace the forward end of a tank resting in said cradle, so as to permit the head of the tank to protrude, said fire wall extending vertically and laterally beyond the radial limits of said opening and together with said foundation, providing a tank-encircling main shield, the lateral extremities of said main shield terminating in forwardly directed wings which together with said main shield define the boundaries of a fire retaining area around said tank 55 head, and an angularly disposed flame diverting lip extending along the upper edge of at least said main shield and directed into said fire retaining area.

4. The combination as claimed in claim 3, 60 wherein the upper edges of said forwardly directed wings are provided with flame-diverting lips forming continuations of the lip on said main shield.

5. The combination as claimed in claim 4 including a continuous flame-diverting lip which

extends along the bounding edges of said main shield and wings.

6. A fire wall for tanks adapted to contain inflammable fluids, comprising a vertically disposed main shield of fire-resistant material, an opening in said shield adapted to embrace the forward end of a tank, so as to permit the head of the tank to protrude, said shield extending vertically and laterally beyond the radial limits of said opening, the lateral extremities of said shield terminating in forwardly directed wings which together with said shield define the boundaries of a fire-retaining area around said tank head, and an angularly disposed flame-diverting lip extending along the upper edge of at least said main shield and directed into said fire retaining area.

7. A fire wall as claimed in claim 6 wherein said angularly disposed lip is continued around the bounding edges of said wings.

8. A combination above ground tank support and fire wall, comprising a solid foundation member, the top of which is provided with a series of recesses forming transverse cradles for the head ends of a corresponding series of horizontal tanks, said foundation being extended vertically to form a continuous fire wall of fire resistant material, a series of openings in said fire wall

adapted to embrace the forward ends of respective tanks resting in said cradles, so as to permit the heads of said tanks to protrude, said fire wall projecting vertically beyond the radial limits of said openings and laterally in both directions, beyond the outermost of said series of openings, and together with said foundation, providing an encircling main shield for each of said tanks, the lateral extremities of said main shield terminating in forwardly directed wings which together with said main shield define the boundaries of a fire resistant area around said tank heads, and an angularly disposed flame-diverting lip extending along the upper edge of at least said main shield and directed into said fire retaining area.
